(57) **CLAIM**

The ornamental design for a bottle, as shown and described.

DESCRIPTION

FIG. 1 is a perspective view of a bottle according to the present invention;

FIG. 2 is a front view of a bottle according to the present invention;

FIG. 3 is a back view of a bottle according to the present invention;

FIG. 4 is a right side view of a bottle according to the present invention;

FIG. 5 is a left side view of a bottle according to the present invention;

FIG. 6 is a top view of a bottle according to the present invention;

FIG. 7 is a bottom view of a bottle according to the present invention; and,

FIG. 8 is a top perspective view of a bottle according to the present invention.

The broken lines on the neck of the claimed design represent threads for a cap and form no part of the claimed design. All other broken lines are for illustrative purposes only.
